UNITED STATES PATENT OFFICE.

THOMAS C. RICHARDS, OF WINSTED, CONNECTICUT.

CURTAIN-ROD.

No. 821,377.

Specification of Letters Patent.

Patented May 22, 1906.

Application filed July 27, 1905. Serial No. 271,497.

To all whom it may concern:

Be it known that I, THOMAS C. RICHARDS, a resident of Winsted, in the county of Litchfield and State of Connecticut, have invented 5 certain new and useful Improvements in Curtain-Rods; and I do hereby declare the following to be a full, clear, and exact description of the invention, such as will enable others skilled in the art to which it appertains to make and use the same.

My invention relates to improvements in curtain-rods, and more particularly to an improved permanently-fixed ornamental end for extension-rods, the object of the invention 15 being to provide an improved construction of end which can be cheaply manufactured and assembled and easily and securely attached to the end of the rod and which will be strong and durable in use.

With this object in view the invention consists in certain novel features of construction and combinations and arrangements of parts, as will be more fully hereinafter described, and pointed out in the claims.

In the accompanying drawings, Figure 1 is a view in elevation illustrating my improvements. Fig. 2 is a view in longitudinal section, and Figs. 3, 4, and 5 are views of details of construction.

1 represents a tubular rod of sheet metal, to which my improved end is secured, as will now be explained.

2 is an ornamental ball, which may be corrugated, as shown, or ornamented in any 35 other manner and provided with openings at its opposite ends to receive a rod 3, which latter is passed through an opening in a disk 4, closing one opening in the ball, and at this same end of the rod it is ribbed or roughened 40 so as to firmly bind when forced into the cylindrical bore of an ornamental head 6 held tightly against the disk. The rod 3 near its opposite end is provided with an annular flange or shoulder 9, located in a depressed

45 portion of a cap 7, and holds the latter tightly against ball 2, closing the opening therein. A concavo-convex washer 8 is inserted on rod 3 against shoulder 9, and the end of the rod is then upset to secure the washer in position.

50 This cap 7 is inserted on the rod 1 with the end of the rod 1 around washer 8, and the cap 7 and rod are contracted to clamp the end thereon, and as the washer 8 will hold the extreme end of rod 1 from being contracted the

55 cap 7 will be securely clamped and the end cannot work off the rod. By this method of

fastening the end it becomes a permanent part of the rod and cannot be removed without the exertion of a great deal of force. The parts are cheaply made and assembled and 60 when once assembled will not separate in any ordinary use.

Slight changes might be made in the general form and arrangement of the parts described without departing from my invention, and hence I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. The combination with an ornamental device having an opening, of a cup seated on the ornamental device and having a depressed portion entering the opening therein, a rod clamped in said cup, a rod passing through the ornamental device and the depressed portion of the cup, and means on the rod engaging the cup and permanently securing the same in place.

2. The combination with an ornamental device, of a rod therethrough, a shoulder on the rod holding a cup against the ornamental 85 device, a washer on the rod in the cup and secured by upsetting the rod, and a tubular curtain-rod in the cup and the latter clamped thereon.

3. A curtain-rod end comprising an ornamental device, a rod therethrough, a head into which a roughened or irregular end of the rod is driven, a cup on the rod, a shoulder on the rod in the cup, and a concavo-convex washer secured in the cup by upsetting the 95 rod thereagainst.

4. A curtain-rod end, comprising an ornamental ball having opposite openings, a disk at one opening, a cup at the other opening, a rod passed through the cup, ball, and disk and having a shoulder in the cup, an ornamental head having a cylindrical bore into which the rod is tightly driven, a concavo-convex washer on the rod in the cup, and said rod upset against the washer.

In testimony whereof I have signed this specification in the presence of two subscribing witnesses.

THOMAS C. RICHARDS.
